REINFORCED EDGE FOR HAT BRIMS

Frank T. Stack and John C. Smith, Norwalk, Conn., assignors to Hat Corporation of America, New York, N. Y., a corporation of Delaware

Application November 23, 1932, Serial No. 644,026

3 Claims. (Cl. 2—178)

This invention refers to felt hats and more particularly to the formation of a reenforced edge on the brims of such hats.

The primary object of the invention is to provide invisible means for holding down, by stitching, the folded-over annular edge portion of the brim and in a manner which will require a relatively small amount of labor to finish the edge after being stitched.

10 Hats having reenforced or thickened edge portions are, at the present time, very popular for both gentlemen's and ladies' use, and are produced in various ways including methods of turning over the edge portion and stitching it down through the two thicknesses of felt. These methods, however, are more or less objectional as the annular row of stitches is usually left exposed or otherwise poorly constructed, which in some instances serves to injure the felt.

20 In securing the folded edge portions of the brim together, in accordance with our invention, we do not employ what would be regarded as a through-and-through stitch, but employ a seam which goes through adjacent face portions of the 25 brim only, and in a way to be entirely covered when the edge or outer portion of the brim is folded over and down.

In order that the invention may be fully understood, we have endeavored to represent in the accompanying drawing by a series of fragmentary illustrations the several steps in the process, and will next proceed to describe the same in detail.

In the said drawing, similar characters of reference will be found to designate like or corresponding parts of the hat body in process, and wherein

35 Fig. 1 shows a fragmentary sectional view on an enlarged scale of a portion of a hat, its brim and edge, as produced in the manufacture of a hat preparatory to the operations of reenforcing the 40 edge of the brim in accordance with our invention.

Fig. 2 shows a further sectional view illustrating the novel manner in which the brim, shown in Fig. 1, of the hat is folded for stitching the two abutting top face portions of the brim together;

45 Fig. 3 shows the next operation of folding the stitched edge portion back on the top face of the brim to formulate a reenforced edge, in accordance with our invention;

50 Fig. 4 represents a somewhat similar sectional view illustrating the completed reenforced edge after being trimmed and pressed;

55 Fig. 5 illustrates a perspective view of a soft fur hat formed in accordance with our invention;

Fig. 6 is somewhat similar to Fig. 1, though illustrates a slight modification wherein the edge portion of the hat brim is shown turned in under the brim, as the preliminary operation, instead of up, in and over, as shown in Fig. 1; and

60 Fig. 7 shows a further fragmentary sectional view of a hat brim having a reenforced edge formed in accordance with the preliminary operation disclosed in Fig. 6.

Our improved process of reenforcing the edge portion of the hat brims is practiced after the hat has been blocked, pounced and ironed, and just prior to being trimmed. At this stage in the manufacture of a fur hat, the brim portion is relatively wider than that of the brim of the finished 70 hat and has a comparatively uneven edge. This edge is obviously pliable and may be readily folded inward, as shown in Fig. 1, as a preliminary step of our process. This first operation upon the brim, as practiced in our preferred form of the 75 invention, is clearly illustrated in Fig. 1, wherein said turned-in brim portion is indicated as 10, the brim proper as 11, and the crown portion of the hat as 12. At this stage in the process, the hat band and sweat band have not yet been attached. 80

The next step in our process is that of closing the annular folded portion 13 together, bending it down and deflecting the annular edge portion 14 outward as shown in Fig. 2, preparatory to the stitching operation whereby a row of 85 stitches 15 is applied as indicated in Fig. 2, and which serves to draw the adjacent annular bent edges 16—16 of the brim together, the stitching 15 being applied through adjacent portions of one side of the fabric so as not to show on the opposite side and whereby the said stitches will be entirely concealed when the outwardly deflected edge portion 14 of the brim, as shown in Fig. 2, is turned in upon the flat surface 11 of the brim, as indicated in Fig. 3. 90

95 The annular edge portion 18, see Fig. 3, of the member 14 is next trimmed off to provide a finished edge 17, as shown in Figs. 4 and 5, which determines the width of the finished reenforced portion of the brim. After the edge portion of the 100 brim has been turned in and is trimmed off, as indicated in Fig. 4, it is then neatly ironed down, to be permanently retained in position by the line of stitching 15 applied between the two adjacent inner surfaces of the reenforced edge of the 105 brim.

110 In view of the foregoing description of the preferred process of forming a reenforced edge on a hat brim, it will readily be seen that a preliminary reversal operation of the edge portion of the brim

may be performed, as indicated in Fig. 6, where-
in the edge portion 10 of the hat brim is turned
in under to form a fold, instead of in over, as
indicated in Fig. 1, in which case the next opera-
5 tion would be that of deflecting the fold upward
and the edge portion outward in a reverse pos-
ition from that shown in Fig. 2, and whereby the
line of stitching would be applied through the
undersurface of the brim instead of the top face,
10 as shown in Fig. 2. In this modified form of the
invention, a substantially similar reenforced edge
is produced in a manner to include a concealed
stitch for holding the folded-in portion of the
brim to the main body of the brim, though in this
15 instance as before suggested, the reinforcement
will lie on the underside of the brim, see Fig. 7,
instead of on the top side, as shown in Figs. 4
and 5. In this respect it will be noted that in
both instances the stitches are not visible, being
20 entirely enclosed by the uncut and imperforate
outer surfaces of the reenforced edge, yet serve
to hold the annular overlapping edge perma-
nently in position.

We make no claim to, and disclaim from the
25 scope of the appended claims, reenforced edges
of brims of felt hats, and particularly make no
claim to, and disclaim from the scope of the ap-
pended claims, reenforced brim edge of the types
disclosed in Letters Patent of the United States
30 #1,791,461.

Having thus described our invention what we
claim and desire to secure by Letters Patent is:

1. In the manufacture of hats, the process of
producing a hat body of felt having a reenforced
35 edge formed of two plies of material, which con-
sists in folding in the annular edge portion of the
hat brim, then bending part of said edge portion
in a way to form an annular fold, and disposing
the annular edge outward and the fold at sub-
40 stantially a right angle to the face of the brim,
stitching together the adjacent annular folded
portions with the stitches passing through the
surface only of the fold, then turning the out-

wardly disposed edge in upon the brim in a way
to cover the row of stitches and form an edge
portion of two thicknesses of material having
outer imperforate surface portions.

2. In the manufacture of hats, the process of
producing a hat body of felt having a reenforced
edge formed of two plies of an integral piece of
material, which consists in folding in the annular
edge portion of the hat brim, then bending part
80 of said edge portion in a way to form an annular
fold, and disposing the annular edge outward,
leaving the fold disposed to one side of the face
of the brim, stitching together the adjacent annular
folded portions with the stitches passing
85 through the outer surfaces only of the said ad-
jacent folds, then turning the outwardly disposed
edge in upon the brim in a way to cover the
row of stitches and form an edge portion of two
thicknesses of material having outer imperforate
90 surface portions, next trimming off the edge of
said inwardly disposed portion, and ironing said
edge portion in a way to cause it to lay snugly
upon the brim.

3. In the manufacture of hats, the process of
producing a hat body of felt having a reenforced
100 edge formed of two plies of the same material,
which consists in folding in the annular edge
portion of the hat brim, then bending part of said
edge portion in a way to form an annular fold,
and disposing the annular edge outward and the
105 fold at substantially a right angle to the face of
the brim, stitching together the adjacent annular
folded portions with the stitches passing through
the surfaces only of the fold, then turning the
outwardly disposed edge in upon the brim in a
110 way to cover the row of stitches and form an
edge portion of two thicknesses of material hav-
ing outer imperforate surface portions, and in
trimming off the edge of said inwardly disposed
portion.
